SURGICAL SUPPORT

Filed Aug. 17, 1927

UNITED STATES PATENT OFFICE

FRANK J. STUART, OF ST. LOUIS, MISSOURI

SURGICAL SUPPORT

Application filed August 17, 1927. Serial No. 213,583.

The invention relates to improvements in hernia pads and the like. It has been known in the prior art to provide a central hard pad or knob-like member to bear upon the hernia or other afflicted part, and it has been a development to provide around such hard pad a soft cushion member, such as an annulus of soft rubber, whereby a maximum pressure of the complete device may be possible without liability of thrusting the hard element too deeply into the tissues. It has also been appreciated that an adjustment of the hard element with respect to the soft cushion is desirable, and devices have been evolved to meet such requirements, examples of which are found in the patent to Forsberg, No. 54,521, May 8th, 1856; McCullom, 1,158,139, October 26, 1915, and Fuller, 453,298, June 2, 1891.

It is an object of my invention to enable the embodiment of a device of this character with the encircling soft cushion adjustable upon the hard pad in a novel and inexpensive manner and also with an absence of structural elements liable to derangement or involving excessive bulk or disagreeable appearance.

It is also an important aim to avoid excessive weight in such devices, and complicated manufacturing operations, and in the attainment of these objects I have also cheapened the article without detracting from its functional merits so as to place it within the reach of the public generally and adaptable to use by persons of inexperience in such manner as to attain the proper functions required of such appliances.

Additional objects, advantages and features of invention reside in the construction, the arrangements and combination of parts as will be understood from the following description and accompanying drawing, wherein

Figure 1 is an elevational view of an appliance constructed in accordance with my invention including means for its securement upon the body of a patient.

Figure 2 is a detail of the annulus showing its form and size detached.

Figure 3 is a cross section of the appliance, the hard pad being in elevation.

Figure 4 is a fragmentary top view of

the pad and mounting as shown in Figure 1, with a portion of the adhesive omitted.

Figure 5 is an elevational view of the hard pad element.

Figure 6 is a vertical sectional view of the appliance showing it as applied to the body of a person.

Figure 7 is a cross section of a modification of the annulus 16.

The figures are the full size of an operative device as marketed.

There is illustrated a hard or semi-hard pad element 10, which in the present instance is hollow and apertured at its body engaging point for use as an applicator of an absorbable, medica, as it serves in retaining a hernia when set thereover, or performing other functions. The pad 10 is ovate in top view as shown in Figure 4, and may be somewhat apple-shaped in longitudinal section and pear-shaped in cross section, as indicated in Figures 1 and 3. It is formed with a flat bottom 11 centrally of which a slight recess 12 is sometimes formed, having angular edges. An attaching means is provided in the form of a sheet of fabric having an adhesive coating 14 throughout on one side, this support being customarily formed of a comparatively broad strip with an enlarged oval end portion 15 shown in Figure 4. The pad is set with its flat bottom side centrally of the enlargement 15 and pressed forcibly thereon. The adhesive coating 14 is of a nature to serve as a permanent attachment of the pad 10 to the fabric, and the central portion of the fabric and adhesive material being embedded in the recess 12 affords a further assurance of adequate anchorage, so that the pad is not likely to slip on the mounting fabric.

The pad 10 is oval in plan and is substantially apple-shaped as viewed in section taken on a plane coincident with the major axis of this oval and perpendicular to the bottom 11; while in a corresponding section on the minor axis of the oval, the pad is in the shape of an egg frustum, the smaller end of the egg being cut off. That is to say, while the lower parts of the pad are convex as viewed in the sections mentioned, it is

important that the curvature is much less than that near the top of the pad, so that the annulus 16 (to be described) does not tend excessively to slip toward the bottom of the 5 pad by contractive stress of the annulus. Fitted around the pad 10 there is an annulus 16, preferably of sponge rubber with a continuous smooth surface or having closely spaced ribs thereon, at the inner side concentric with the axis of the annulus, the 10 annulus being formed of material of maximum elasticity so as to provide a soft cushion to engage the body of the wearer. Initially, the opening through the annulus 16 15 is much smaller than the cross sectional dimension of the pad 16 to be engaged, so that the annulus fits snugly and with ample frictional bearing upon the pad 10. The annulus 16 is circular in cross section initially, 20 but by reason of the manner of its fit upon the part 10, this cross sectional shape is deformed, as shown in Figure 3, so that a large bearing surface is obtained between the annulus 16 and pad 10. Consequently, the annulus 16 will remain wherever adjusted between the base of the pad 10 and its outer part, within the range of adjustments desirable in such appliances. It is desirable 25 that the surfaces of the sides of the pad shall diverge outwardly from the base in order to prevent casual movement of the annulus 16 toward the body-engaging portion of the pad 10 under exigencies of body movement and pressure variously exerted upon the device 30 externally of the wearer. At the same time, in applying this device in accordance with practices understood in the art, it will be apparent that the annulus 16 is also securely held by the adhesive fabric in proper operative 35 relation to the body of the wearer.

If desired, a multiplicity of circumscribing fine ribs or serrations 17-18 may be formed respectively upon the pad 10 and on the annulus 16, as above mentioned, and 40 shown in Figures 5, and 7. Where the ribs 17 are formed on the pad, when the annulus 16 is put in place, a portion of the material of the annulus will sink between the ribs or serrations and thereby be held against movement transversely of the ribs. If the ribs are 45 also formed on the annulus 16 a very positive adjustment may be secured.

In the use of the pad 10 in connection with attaching means such as here shown, it is 50 customary to warm the adhesive and adjust the part 10 properly upon the hernia or other affected part, drawing the adhesive fabric outwardly and pressing it securely upon the skin of the wearer—the muscular tissues being 55 in a relaxed condition—while the pad is held in proper bearing upon the body. In consequence, the pad is then held in place without the use of laces, belts, or other fastenings. The annulus 16 is included between 60 the body and the adhesive support, which is

extended suitably beyond the annulus 16 to permit it to be properly applied to the epidermis.

It will be understood that in some cases it is desirable for the pad 10 to project more beyond the guarding cushion 16 than in other cases. This is especially true where much adipose tissue intervenes between the epidermis and the peritoneum or abdominal wall. For a maximum projection of the pad 10, the annulus 16 is pressed toward the base of the pad until the desired projection is attained, while if a minimum projection is desired, the annulus 16 is adjusted inwardly toward the portion of major diameter in the pad (see dotted position in Figure 1). These adjustments being made before the appliance is adjusted upon the person, and before the adhesive is drawn into contact with the annulus 16, when the adhesive is drawn taut and then brought inwardly upon the annulus the latter is secured positively in the position to which it is adjusted upon the pad, and the subsequent application of the extreme edge portions of the adhesive fabric to the body of the wearer additionally retains the annulus in proper place. At the same time the annulus 16 itself supports the pad 10 resiliently by reason of the indirect connection between the adhesive fabric and the bottom of the pad 10, and this affords a resilient support of the pad 10 without, however, involving liability of displacement of the pad 10 from its exact adjustment upon the body of the person applied, as is apparent. This has special functional value in enhancing the massaging action of the pad 10, a certain amount of relative movement of the pad 10 upon the affected part being recognized as advantageous as long as it is properly limited. Also the annulus 16 by this manner of mounting exerts a gentle working of the tissues adjacent the area of bearing of the pad 10.

It will be seen that without the use of truss, belt, mounting metal, or other rigid mounting and without the use of levers, screws or the like, I have attained the provision of a relatively adjustable pad and cushion annulus meeting the requirements of the surgical uses contemplated, and at the same time have provided an extremely light, simple and comparatively inexpensive appliance having the advantages sought and heretofore attained only in more complicated form unsuited to wear upon the person beneath clothing and also distasteful because of the machine-like appearance which the prior devices have presented.

The top part of the pad 10 will ordinarily be hard, or relatively hard, but in cases where so indicated by medical or surgical requirements the outer one-quarter or one-third may be more or less flexible.

The peculiar and novel construction of the surgical support brings about automatic

massage through automatic action of the pad 10 and annulus 16, on the flexible fabric strip, with the adhesive mass spread thereon. The flexible fabric strip, holding the pad 10 and annulus 16 firmly against the muscles and tissues, and over the opening, serves every intent and purpose, so far as local pressure and retention of the viscera, is concerned; further, the fabric being flexible there is a certain space left immediately surrounding the annulus 16 sufficient to permit both pad 10 and annulus 16 to move—not translatively on the epidermis, but with an oscillatory, or vibratory motion, caused by inhaling and exhaling of the breath, which causes the entire diaphragm—including the abdominal cavity—to contract and expand with each respiratory movement, producing that natural motion, automatically brought about by the peculiar diaphragmatic rise and fall of the diaphragm. Various other movements of the body incident to the conscious activities of the wearer contribute to this effect.

It is to be remembered that abdominal hernia is caused by a relaxation, weakening and consequent separation of certain muscular fibres and tissues surrounding certain natural openings, in the abdominal walls, the usual points of occurrence being the inguinal opening; the femoral opening and the umbilical opening. Also be it remembered that muscles can be strengthened by application thereto of the proper stimuli—one of the most common, and perhaps the best form of stimulus, being massage.

The novel construction, application and use of the surgical support, therefore, produces and furnishes the massage; hence the proper stimuli to the affected muscles tending to curative outcome of the use of my appliance.

I claim:

1. In a device of the character described, a central hard pad member, and a thick soft and elastic annulus fitted snugly thereon, the pad being of an altitude from bottom to top much greater than the corresponding measurement of the annulus, said pad having a series of irregularities on its lateral surfaces spaced from the top of the pad and being constructed and adapted to be embedded in the engaged part of the annulus by contraction of the latter, to prevent casual slipping of the annulus from adjusted positions on the pad, the lower side portions of said pad having a mutual relation between diametrically opposite portions such as to support the annulus in positions spaced from the bottom of the pad, whereby the annulus will be held adjustably with respect to the top of the pad, said annulus being of sufficient tensile strength to transmit effective pressure from the annulus to

the person of the wearer by its inherent contractile quality acting upon the pad.

2. The structure of claim 1 in which the irregularities on the surface of the pad are uniformly spaced in a direction from bottom to top of the pad, and said annulus is formed with corresponding irregularities adapted to intermesh with those of the pad.

In testimony whereof I affix my signature.

75
